HINGE CONSTRUCTION

Harry Rodemeyer, Detroit, Mich.

Application February 23, 1932, Serial No. 594,661

3 Claims. (Cl. 16—172)

This invention relates generally to hinges and more particularly to improvements in the construction thereof tending to simplify and render the same more efficient.

5 One of the principal objects of this invention resides in the provision of a readily detachable pivotal connection between the cooperating hinge parts designed to secure the latter parts together in such a manner as to eliminate any tendency 10 for rattle and at the same time fashioned to offer the minimum resistance to relative movement of the parts.

The invention contemplates securing the foregoing features as well as reducing the number of 15 parts of the hinge to a minimum by providing a construction wherein one of the cooperating hinge parts is formed with a ball portion fashioned to have a snap engagement with a corresponding socket portion formed integral with the 20 other hinge part.

Another object of this invention resides in the provision of means associated with the cooperating interengaging portions aforesaid for locking the corresponding hinge parts in assembled relation 25 during the normal operation of the hinge.

Another advantageous feature of the present invention resides in the provision of a hinge assembly wherein the socket portion of one of the hinge parts is formed with a plurality of slots 30 therein arranged to increase the flexibility of the socket and thereby facilitate engagement of the ball portion on the other hinge part therewith.

Another object of the present invention resides in the novel means provided herein for concealing 35 the slots fashioned in the socket set forth in the previous paragraph and thereby enhance the general appearance of the hinge.

A further object of this invention which contributes materially to the commercial value and 40 acceptability of the present invention resides in the provision of means on the hinge for limiting relative pivotal movement of the cooperating parts thereof and as a consequence serving the purpose of a door stop.

45 A still further advantageous feature of the present invention consists in the provision of a hinge capable of being applied in such a manner that the pivotal connection between the cooperating hinge parts is completely concealed from view.

With the foregoing as well as other objects in view, the invention resides in the peculiar constructions of the various types of hinge assemblies 50 illustrated herein which will be made more apparent as this description proceeds, especially when

considered in connection with the accompanying drawings, wherein:

Figure 1 is a fragmentary side elevational view 60 of a hinge assembly constructed in accordance with this invention;

Figure 2 is a sectional view taken substantially on the plane indicated by the line 2—2 of Figure 1;

Figure 3 is a sectional view similar to Figure 2 showing the relative positions of the hinge parts 65 just prior to assembling the latter and illustrating the means for normally locking the hinge parts in assembled position;

Figure 4 is a perspective view of the construction shown in Figure 1;

Figure 5 is a sectional view taken substantially on the line 5—5 of Figure 1;

Figure 6 is a longitudinal sectional view through 75 a hinge assembly showing a slightly modified form of construction;

Figure 7 is a sectional view taken substantially on the line 7—7 of Figure 6;

Figure 8 is a side elevational view of another modified form of hinge construction;

Figure 9 is a fragmentary side elevational view 80 of a door and jamb assembly illustrating another modified form of hinge construction;

Figure 10 is a sectional view taken on the plane indicated by the line 10—10 of Figure 9;

Figure 11 is a sectional view taken substantially 85 on the plane indicated by the line 11—11 of Figure 10;

Figure 12 is a sectional view showing a further modification of the present invention;

Figure 13 is also a sectional view showing still 90 another modified form of hinge construction;

Figure 14 is a sectional view taken on the plane indicated by the line 14—14 of Figure 13.

Referring now more in detail to the drawings and with special reference to the modification of 95 the invention illustrated in Figures 1 to 5, inclusive, it will be noted that I have illustrated in Figure 1 a hinge assembly 15 comprising cooperating relatively movable hinge parts 16 and 17 having interengaging portions at adjacent 100 ends thereof providing a pivotal connection therebetween. The pivotal connection between the hinge parts comprises a substantially spherical ball portion 18 formed integral with the part 16 and engageable within a socket portion 19 formed 105 integral with the cooperating hinge part 17. As shown particularly in Figure 3, the opening 20 in the socket 19 through which the ball 18 is extended upon engaging the same with the socket, is substantially less in cross sectional area than the 110

maximum diameter of the ball so as to effect a snap engagement of the ball within the socket. It will also be apparent from Figure 2 of the drawings that the radius of the interior wall of the socket is so determined with respect to the radius of the ball as to form a bearing for the ball throughout substantially the entire surface of the latter and to also secure the same under a slight tension within the socket. The foregoing arrangement is such as to not only provide a readily detachable pivotal connection between the cooperating hinge parts, but to also secure the parts together in such a manner as to eliminate any tendency for the ball to rattle within the socket. It will further be observed that by reason of the ball and socket connection between the hinge parts, one of the latter may assume an angular position relative to the other without interfering with the hinge action. This latter feature is especially advantageous since it compensates for limited misalignment of the hinge parts during assembly.

In order to facilitate snapping the ball 18 within the socket and at the same time prevent accidental disengagement of the ball from the socket in the normal relative positions of the hinge parts, one side of the ball may be formed with a substantially flat surface 21 fashioned to engage a corresponding flat surface 22 formed at one side of the opening 20. The cooperating flat surfaces 21 and 22 reduce the extent of expansion of the lip of the socket necessary to effect the desired snap engagement of the ball therewith and are so positioned as to register with each other only in the abnormal relative positions of the hinge parts so that after the latter are assembled and moved to their normal operating positions, the flats are out of registration, with the result that the parts are securely held together.

While the hinge assembly 15 may be formed in any suitable manner, nevertheless, I have shown the same in Figures 1 to 5, inclusive, as being developed from sheet metal. In detail, the hinge part 16 is preferably fashioned by bending a strip of relatively light gage stock to form a double thickness and by subsequently extruding the two thicknesses of stock at the bend to form the spherical ball 18. The hinge part 17 is similarly fashioned except that the stock is fashioned at the bend to form a socket for receiving the ball in the manner hereinbefore set forth. In order to provide for attaching the hinge parts to the members with which the same are adapted to be employed, the inner thickness of metal of each hinge part, designated by the reference characters 23 and 23' in Figure 5, is provided with an opening 24 of greater diameter than the screw 25 or other fastener element adapted to extend through the opening 24. The outer thickness of metal of each of the hinge parts opposite the openings 24 is punched inwardly as at 26 to provide openings therethrough of sufficient dimension to receive the fastener elements 25 and to form recesses 27 in the hinge parts simulating counterbored portions for receiving the heads of the fastener elements flush with the outer surfaces of said hinge parts. In forming the hinge from sheet metal, the cooperating bearing surfaces of the ball and socket portions are preferably coined so as to increase the density of the metal and thereby produce wear resisting surfaces.

The modification illustrated in Figures 6 and 7 differs from the foregoing construction in that the cooperating hinge parts 30 and 31 are formed

of relatively heavy gage stock and the ball 32 on the hinge part 30 is retained under a slight tension in the socket 33 formed in the hinge part 31 by means of a spring retainer 34. The spring retainer 34 is located within an annular recess 35 formed in the inner surface of the socket 33 adjacent the lip of the latter. The depth of the recess 35 is such as to provide sufficient expansion of the spring retainer 34 to permit the ball 32 to be extended therethrough into the socket, and the location of the recess in the socket is accurately predetermined so as to support the spring in a position to maintain the ball in the socket under a slight tension.

The construction illustrated in Figure 8 differs from the modification illustrated in Figures 6 and 7 in that the spring retainer 34 is omitted and the ball 36 is snapped into engagement with the socket 37 in the same manner as pointed out in connection with the first described form of the invention. The hinge shown in Figure 8, however, is preferably formed of relatively heavy gage stock and accordingly, in order to obtain the desired flexibility of the side walls of the socket, the latter walls are formed with a plurality of circumferentially spaced slots 38 therein. The slots extend inwardly from the lip of the socket and cooperate to form a plurality of spring fingers 39 capable of sufficient deflection to permit the passage of the ball past the lip into the socket and to retain the ball in assembled relation with the socket under a slight tension. The spring fingers and slots in the socket are normally concealed by means of a cover 40 fashioned to snap over the outer surface of the socket as clearly shown in Figure 8.

In Figures 9 to 11, inclusive, I have shown a hinge construction capable of being applied in such a manner that the joint between the cooperating hinge parts is thoroughly concealed from view. In illustrating the present modification of hinge construction, I have shown the same as applied to a door 42 and a jamb 43. In detail, the edge of the jamb 43 adjacent the swinging edge of the door 42 is provided with a recess 44 within which the hinge part 45 is secured to the jamb by means of the fastener elements 46. The cooperating hinge part 47 is provided with a body portion 48 arranged within the recess 44 substantially flush with the outer side wall 49 of the jamb 43 and having an inwardly extending attaching flange 50 secured to the edge of the door 42 adjacent the jamb by means of the fastener elements 51. The body portion 48 is formed with an inwardly extending socket portion 52 fashioned to have a snap engagement with a ball 53 formed integral with and extending upwardly from the hinge part 45. In the event the socket portion 52 is formed of relatively heavy gage stock, the same may be slotted as at 54 to facilitate snap engagement with the ball in the same manner as hereinbefore described in connection with the modification shown in Figure 8. As will be observed from Figure 9, the recess 44 is preferably provided with an upwardly projecting extension 55 of sufficient dimension to permit the necessary vertical travel of the hinge part 47 relative to the hinge part 45 upon assembling or removing the former from the latter. The extension 55 is normally concealed by means of an auxiliary plate 56 secured to the jamb substantially flush with the outer surfaces of the latter and hinge part 48. The exterior surfaces of the plate 56 and body portion 48 of the hinge part 47 may be finished in the same manner as

the jamb and door so as to simulate in appearance portions of the latter.

The construction of hinge shown in Figures 9 to 11, inclusive, is such as to permit readily employing a door stop in association therewith. As shown particularly in Figure 10, an extension 60 is provided on the hinge part 47 beyond the pivotal connection between the latter and cooperating hinge part 45 for engaging a plunger 57 on the latter part upon swinging the door to its open position. The plunger 57 is slidably mounted within a counterbored boss 58 formed on the hinge part 45 inwardly of the ball 53 and movement thereof within the boss by the extension 60 is resisted by a spring 61 located within the boss in rear of the plunger. The foregoing arrangement provides a relatively simple and inexpensive door check capable of yieldably restricting the extent of movement of the door 42 to its open position.

In the modification illustrated in Figure 12, I have shown the manner in which the basic principles of the hinge assemblies specified above may be employed for swivelly connecting a swinging door 62 to its support. In detail, the door 62 is provided with a fitting 63 having a portion embracing the lower edge of the door and formed with a spherical ball 64 projecting below the latter edge of the door for snap engagement with a socket 65 suitably secured to a fixed support. The upper end of the door (not shown) may be similarly connected, thereby providing a compact and relatively simple swivel connection between the door and its associated supports.

In the construction shown in Figure 13, I have illustrated the manner in which my improved hinge construction may be employed for hingedly connecting one edge of a door to a jamb in such a manner as to provide for swinging movement of the door both inwardly and outwardly. In detail, the connection illustrated herein comprises essentially three parts 66, 67 and 68 compactly located between the adjacent edges of the jamb and door. The part 66 is preferably secured to the edge of the jamb and is provided with a ball 69 projecting beyond the outer side of the jamb for snap engagement with a socket 70 formed on the outer end of the connecting part 68. The inner end of the connecting part 68 is preferably formed with a ball 71 similar to the ball 69 and adapted to snap into engagement with a socket 72 formed integral with the hinge part 67 and projecting beyond the inner sides of the door and jamb.

While several embodiments of the present invention have been hereinbefore described, it will be noted that all of the modifications are similar in basic principle in that each of the same incorporate cooperating hinge parts having corresponding ball and socket portions adapted to

snap into engagement with each other to provide a readily detachable swivel connection between the hinge parts. It will further be apparent from the preceding description that in each of the embodiments of the invention, the spherical ball portions are held in engagement with the sockets under a tension sufficient to prevent rattling of the parts, but insufficient to appreciably effect relative swinging movement of the hinge parts. In addition to the foregoing, it is to be noted that the socket portions of each of the foregoing hinges are formed with serrations therein for retaining a suitable graphite compound or other permanent lubricant.

What I claim as my invention is:

1. A hinge having a pair of hinge parts and having a readily detachable pivotal connection between said parts comprising a ball projecting from one of said parts and a socket on the other of said parts having a portion forming a recess corresponding in shape to the ball and having a portion of less diameter than the maximum diameter of the ball formed with a plurality of circumferentially spaced slots therein to provide for snapping the ball into the recess, and a cover for said socket fashioned to conceal said slots.

2. A hinge having a pair of hinge parts and having a readily detachable connection between said parts comprising a ball projecting from one of said parts, a socket on the other of said parts corresponding in shape to the ball for receiving the latter and having a portion adjacent the lip thereof of less diameter than the ball and engageable with the ball to frictionally hold the latter in said socket, said lip formed with a plurality of circumferentially spaced slots providing for snapping the ball into engagement with the socket, and said slots having a width substantially less than the width of the metal therebetween so as to provide the maximum bearing surface on the socket for engagement with the ball.

3. A hinge having a pair of hinge parts and having a readily detachable connection between said parts comprising a spherical ball projecting from one of said parts, a socket on the other of the hinge parts receiving the ball providing a substantially continuous bearing surface for engagement with the ball and providing a universal connection between the hinge parts, said socket having a resilient portion adjacent the lip thereof of less diameter than the ball providing for snapping the ball into engagement with the socket and engageable with the ball to frictionally hold the latter in bearing engagement with the interior surface of the socket.

HARRY RODEMEYER.
